ABSTRACT: A condition responsive pure fluid oscillator comprising a power nozzle for issuing a power stream, at least one output passage for selectively receiving the power stream, and a hollow control tube aligned generally perpendicular to the power stream flow. Standing waves are produced in the control tube in response to the power stream flowing past the tube mouth. The standing waves produce pressure differentials causing the power stream to oscillate, the frequency of oscillation being adjustable by means of a movable piston within the control tube. The position of the piston in the control tube is made responsive to an external control. The device may serve as a displacement transducer when clearance is provided between the wall of the control tube and the piston, the piston thereby varying the output frequency as a function of its position along the longitudinal axis of the control tube. The oscillator may be employed as a pneumatic eye sensing element whereby the piston is removed and a sensing stream is directed into the control tube from a location external to the oscillator, the oscillator oscillating or not as a function of the presence or absence of the sensing stream at the control tube.

CONDITION RESPONSIVE PURE FLUID OSCILLATOR

BACKGROUND OF THE INVENTION

The present invention relates to fluid oscillators of the organ pipe type and, more particularly, to organ pipe oscillators employed as highly sensitive condition responsive devices.

An organ pipe fluid oscillator operates on the principle that a power stream may be cyclically deflected by standing waves generated in a resonance tube across the mouth of which the power stream is caused to flow. Such a device is disclosed in U. S. Pat. No. 3,340,884 to R. W. Warren and R. E. Bowles. Oscillators of this type are known to exhibit extremely high frequency stability characteristics over predetermined power stream pressure ranges, since the frequency over a given pressure range is determined almost solely by the effective length of the resonance tube. Consequently organ pipe oscillators are employed in applications where cyclical fluid pressure signals of stable frequency are required.

It has been discovered as part of the present invention that, in addition to serving as highly stable frequency sources, organ pipe fluid oscillators may be modified so as to serve as highly sensitive condition responsive devices, such devices having a wide variety of practical applications. In one such application, the device may be employed as an accelerometer, and more specifically, as a highly sensitive accelerometer to be employed in space craft travelling beyond the earth's gravitational field. Another application for the control responsive organ pipe oscillator relates to extremely sensitive object detection and, more particularly, to what are known in the fluidics art as "pneumatic eyes."

It is an object of the present invention to provide an organ pipe oscillator sensitive to external conditions.

It is another object of the present invention to provide a displacement transducer, a speedometer and an accelerometer, each employing a pure fluid organ pipe oscillator.

It is still another object of the present invention to provide a pneumatic eye employing a condition responsive pure fluid oscillator.

SUMMARY OF THE INVENTION

The condition responsive pure fluid organ pipe oscillator of the present invention utilizes a translatable piston in the resonant or control tube of the organ pipe oscillator, the position of the piston within the tube being made dependent upon a condition to be sensed.

In the alternative, the oscillations of the organ pipe oscillator may be destroyed, for instance, by destroying the standing wave patterns in the organ pipe and thus, provide an on-off or go-no-go type of sensor of external conditions. In employing the organ pipe oscillator as a displacement transducer in accordance with the principles of the present invention, the piston inserted within the resonance tube of the oscillator is of such size as to provide clearance between the inner walls of the tube and the piston. Displacement of the piston along the longitudinal axis of the resonant control tube of the oscillator produces changes in frequency of the oscillator. The rate of frequency change is a measure of velocity along the control tube axis. Acceleration may be monitored by providing a spring in the control tube which tends to restore the piston to a vertical position. For most efficient and sensitive operation, the oscillator is designed so that the relationship between the orifices of the power nozzle, output passage, and resonant control tube are such that there is substantially no power stream fluid exhausted through the resonant control tube.

In utilizing the condition responsive organ pipe oscillator as a pneumatic eye, a fluid jet is directed toward the open end of the resonant control tube from a location external to the oscillator. The oscillator can be made to oscillate or not in accordance with the flow or interruption of flow of fluid from the jet into the control tube, the interruption resulting from detection of an object in the path of the jet.

BRIEF DESCRIPTION OF THE DRAWINGS

The above and still further objects, features and advantages of the present invention will become apparent upon consideration of the following detailed description of several specific embodiments thereof, especially when taken in conjunction with the accompanying drawings, in which:

FIG. 1 is a partially diagrammatic plan view of a condition responsive organ pipe oscillator;

10 FIG. 2 is a plan view of an organ pipe oscillator employed as a displacement transducer; and

FIG. 3 is a perspective view of an organ pipe oscillator employed as a pneumatic eye.

15 DESCRIPTION OF THE PREFERRED EMBODIMENT

Referring now to FIG. 1 of the accompanying drawings, there is illustrated a pure fluid organ pipe oscillator 10 arranged to provide a variable frequency output signal as a function of a condition or control function to be monitored.

20 Oscillator 10 is typically constructed of two or more laminated sheets of plastic, metallic, ceramic, or other suitable material. For purposes of illustration, a single sheet is illustrated having the requisite passages, orifices and grooves defined therein. It is to be understood that, where necessary, a top sheet, serving as a fluid seal, is to be placed over the single sheet to seal the openings and passages described hereinbelow.

A fluid power source, not illustrated, is connected to a tube

25 20 supplying pressurized fluid to a power nozzle 21. Power nozzle 21 issues a power stream into a region 23, the left side of which (as viewed in FIG. 1) is open to ambient pressure. The downstream end of region 23 has a pair of output

30 25 and 27 communicating therewith. Output passage 25 is disposed in substantial axial alignment with power nozzle 21, output passage 27 is disposed slightly to the left of passage 25 and at a small acute angle with respect thereto. Output passages 25 and 27 communicate with a pair of output tubes

35 29 and 31, respectively, which in turn may be connected to a

40 fluid sensing and/or utilization device 32.

A passage 33, substantially wider than either of the output 45 passages 25 and 27 is formed on the right side of power nozzle 21 in region 23 (as viewed in FIG. 1) and communicates with a control tube 35 axially aligned therewith. The cross-sectional configuration of control tube 35 is illustrated as being circular; however, it is to be understood that square, rectangular, elliptical, or any convenient cross-sectional configuration

50 may be employed. The cross-sectional configuration of passage 33 need not be the same as that of tube 35; and in fact, is illustrated as being rectangular in FIG. 1 whereas control

55 tube 35 is circular. The length of control tube 35 is chosen to provide the minimum desired frequency for oscillator 10 in accordance with the principles to be described below. The outer end 36 of tube 35, i.e. the end remote from region 23, may either be open to ambient pressure, as illustrated, or closed. If closed, a sufficient opening should be provided in tube end 36 if necessary to accommodate means for driving a piston 37 located in the tube.

60 Piston 37, having substantially the same cross-sectional configuration as control tube 35, is disposed within the translatable along the axis of the control tube.

65 Clearance may be provided or not between the inner wall of control tube 35 and the periphery of piston 37. The effect of providing such clearance is discussed below. The embodiment of FIG. 1 is illustrated without substantial clearance between the piston and the tube wall. The position of piston 37 within the control tube 35 is determined by an externally supplied control or condition signal acting through driver member 39.

70 Driver member 39 may be any conventional means for displacing a piston shaft as a function of an input control or condition signal. An example of such a device may be found in FIG. 9 of the U. S. Pat No. 3,122,165 to B. M. Horton, such device being a pure fluid amplifier which responds to a differential pressure across its control ports to axially displace a

shaft. An electromechanical or electromagnetic driver may be employed to provide electrofluid interfaces or simply a mechanical driver may be employed to provide a mechanical fluid interface.

The oscillation frequency for oscillator 10 is determined by the effective length of control tube 35 which, in turn, is determined by the position of piston 37. Specifically, as the power stream issues into region 23, a disturbance is created at the mouth of control tube 35 which produces standing waves in the tube. Since control tube 35 is effectively closed by piston 37, the standing waves are produced in accordance with the closed tube resonance mode. The alternate condensations and rarefactions travelling longitudinally in control tube 35 produce cyclical pressure differentials across the power stream issued by nozzle 21 so as to cause the power stream to oscillate. The frequency of oscillation is determined both by the effective length of tube 35 and the power stream pressure. Specifically, the fundamental frequency of closed control pipe 35 is equal to the velocity of sound divided by four times the effective length of the pipe. As the pressure of the power stream is increased successively higher harmonics of the fundamental frequency become dominant to control the oscillation frequency of the power stream. In accordance with closed pipe resonance, the first overtone is at three times the velocity of sound divided by four times the effective length of the control tube, the second overtone is five times the velocity of sound divided by four times the effective length of the control tube, and the n th overtone is equal to $(2n+1)$ times the velocity of sound divided by four times the effective length of the control tube.

The unit 10 in FIG. 1 is inherently a monostable device in that the power stream is normally directed toward output passage 25 and requires continued action by a deflecting force in order to be directed toward output passage 27. The present invention is not to be deemed limited to monostable devices, however, since it should be clear to those skilled in the art that other fluidic element configurations may be equally adapted to operate as organ pipe oscillators. For example, the output passages may be disposed symmetrically on either side of the centerline of power nozzle 21; or the number of output passages may be changed to one, three, etc. sidewalls may be provided in region 23 in order that the boundary layer lock-on phenomenon may be utilized to advantage so as to provide monostable or bistable operation; and so on.

The oscillating power stream produces an oscillating pressure differential between output tubes 29 and 31. Utilization device 32 may be a pressure sensitive device responsive to frequency or frequency difference. Device 32 may either register an indication in terms of the control function or condition being monitored or may alternatively be part of a closed feedback loop whereby it provides a control signal to modify the condition which provides the control signal applied to driver member 39. In addition to the output pressure differential provided across tubes 29, 31, an acoustic responsive device 40 may be positioned adjacent the left side of region 23 so as to receive the acoustic vibrations transmitted by the oscillating power stream. These acoustic vibrations may be transduced by device 40 into fluid or electrical signals as desired. Device 40, like device 32, may be utilized for either indication or control functions as described. Alternatively, the walls of the chamber 23 to the left of the centerline of the power nozzle 21 may form an exponential horn to enhance the radiation of sound.

One possible application for the embodiment of FIG. 1 is as an output device for a vortex rate sensor. The control signal applied to driver element 39 may be a fluid pressure differential output signal from a vortex rate sensor such as is provided in U. S. Pat. No. 3,320,815, the differential pressure being proportional to the angular rate of rotation of the rate sensor. If driver element 39 is then the amplifier of FIG. 9 of the above-referenced Horton U. S. Pat. No. 3,122,165, the drive shaft for piston 37 will be displaced from a neutral position as a function of the rotational rate of the vortex rate sen-

sor and the output frequency at passages 29 and 31 will be a measure of this rotational rate. By integrating or differentiating the signal corresponding to angular rate, measures of angular displacement and acceleration respectively may be achieved.

The embodiment of FIG. 1 may also serve as a liquid level sensor. Specifically, where tube 35 is disposed in a tank of liquid such that the liquid level rises in the tube as it rises in the tank, the frequency of oscillator 10 will change as a function of the liquid level. For this application, the liquid level alone without piston 37 may be used to vary the oscillator frequency, or piston 37 may be employed as a float in tube 35.

As mentioned above, for certain applications, it is desirable that clearance be provided between piston 37 and the inner walls of tube 35. If clearance is so provided, most efficient operation of oscillator 10 is achieved where negligible amounts of power stream fluid flow into control tube 35. The relative sizes of the ingress orifices of output passages 25 and 27 and the egress orifice of power nozzle 21 may be designed to eliminate power stream flow into control tube 35. Specifically, if output passages 25 and 27 are at least equal to or greater than the width of nozzle 21 or if region 23 is sufficiently vented to ambient, there is insufficient back pressure produced in region 23 to cause power stream flow into control tube 35.

An example wherein clearance between the piston and control tube is utilized in the condition responsive organ pipe oscillator of the present invention is illustrated in FIG. 2. 30 Oscillator 10', which is the same as oscillator 10 of FIG. 1, employs piston 37' in control tube 35' wherein the piston is somewhat smaller in cross section than the control tube so as to provide clearance. In this way, translation of the piston 37' within the control tube 35' is achieved with minimum frictional engagement therebetween. Of course, if the device in FIG. 2 is operated in an environment subject to the gravitational field of the earth, there will be some frictional engagement between the inner wall of tube 35' and the piston 37' by virtue of the gravitational pull on the piston. Still, however, 40 there will be a translation of piston 37' within the control tube whenever there is movement of the device 10' along the longitudinal axis of control tube 35. The output frequency is therefore dependent upon the position of piston 37'. Operation of the device of FIG. 2 as a displacement transducer is optimized, of course, in an environment which is not subject to gravitational forces such as outer space, so that translatory motion of piston 37' within tube 35' is substantially unaffected by frictional engagement therebetween. End 36' of tube 35' should be closed or at least partially restricted to prevent loss of piston 37'. If necessary or desired, an air-bearing arrangement may be provided and low force centering springs or magnets may be employed to provide a zero-acceleration frequency.

55 The operation of the device of FIG. 2 with respect to frequency variations is substantially the same as that for FIG. 1 described in detail above, the major difference being that piston 37' is translated solely by the forces produced upon movement of device 10' longitudinally of tube 35. The output signals produced by device 10' in FIG. 2 may be utilized in the same way as discussed above for the output signals, both acoustic and fluid, in FIG. 1.

Oscillator 10' may be employed to monitor velocity along the axis of control tube 35' if the rate of change of the output 60 frequency is monitored rather than the frequency itself. In addition, oscillator 10' may be utilized to monitor acceleration along the axis of control tube 35' by employing means for providing a restoring force for piston 37'. Specifically, a pair of springs secured between piston 37' and respective opposite 65 ends of control tube 35' would provide a force tending to restore piston 37' to a neutral position in response to displacement of the piston in the control tube, the restoring force being proportional to the displacement. Calibration of the output signals in terms of acceleration, velocity or displacement 70 may be achieved by conventional differentiation techniques.

Referring now to FIG. 3, there is illustrated a condition responsive organ pipe oscillator utilized as a pneumatic eye. Specifically, oscillator 10" is configured substantially the same as oscillator 10 of FIG. 1. Control tube 35" extends from oscillator 10" in a manner similar to the extension of control tube 35 from oscillator 10 in FIG. 1. Control tube 35" is open at end 36" and has no piston or other member disposed therein. A nozzle 41 is disposed in coaxial alignment with control tube 35" and is connected to a suitable source of fluid pressure (not illustrated) so as to issue an air stream into end 36" and through control tube 35". As will be explained in greater detail below, nozzle 41 need not be in coaxial alignment with control tube 35" as long as the two are positioned so that the air stream from nozzle 41 can disturb the standing wave pattern in the control tube 35".

The frequency of oscillation of oscillator 10" is determined by the fluid pressure applied to pipe 20 and the standing wave pattern for an open tube. Specifically, the fundamental frequency of oscillator 10" is equal to the velocity of sound divided by twice the length of tube 35". The first overtone is equal to the velocity of sound divided by the pipe length; the second overtone is equal to three times the velocity of sound divided by two times the pipe length; the n th overtone is equal to $(n+1)$ times the velocity of sound divided by two times the pipe length. The predominant overtone is determined by the pressure at tube 20, the greater the pressure the higher the overtone. Once oscillator 10" is set for operation at a predetermined frequency, the pressure of the control stream issuing from nozzle 41 may be made sufficiently great as to overcome the effects of standing waves generated in control tube 35", in effect reducing the effective length of tube 35" to zero. When the control stream is received by tube 35", the standing wave patterns in the tube are destroyed and the oscillations cease. It may be readily seen, therefore, that oscillator 10", in conjunction with the jet issuing from nozzle 41, comprises a pneumatic eye which detects the presence of an object between nozzle 41 and control tube 35"; the oscillator is enabled when a detected object is in blocking relationship between the nozzle 41 and tube 35" and is inhibited when the control stream from nozzle 41 is not blocked.

The pneumatic eye of FIG. 3 may be made substantially more sensitive to detected objects than prior art pneumatic eyes, such as the pneumatic eye disclosed in U. S. Pat. No. 3,258,023 to R. E. Bowles. In the Bowles pneumatic eye, a monostable fluidic device normally issues a power stream from a first of two output passages. A detection stream is at the outlet end of the first of said outlet passages and, when not blocked, back loads the passage to switch the power stream to the second output passage. The pressure of the detection stream must be sufficiently great to back load the first of said outlet passages. The pressure of applicant's detection stream need not be nearly so great however because oscillator 10" can be adjusted to respond to even a slight disturbance in control tube 35". The extreme sensitivity of applicant's pneumatic eye is made possible by the fact that the organ pipe oscillator 10" is capable of operating at discrete frequencies, namely the fundamental and various overtones thereof. Specifically, for a given range of power stream pressures, the fundamental frequency will be dominant to control oscillation of the power stream. At a higher range of input pressures the first overtone dominates, at a still higher range of input pressures the second overtone dominates, and so on. A very small, but critical range of pressures exists between each of the above-defined pressure ranges, the pressure in these critical ranges being such that the power stream is rendered nonoscillatory. If the power stream pressure is set at one of these critical ranges between oscillatory modes for oscillator 10", merely the slightest disturbance in control tube 35" renders the power stream oscillatory.

Employing the above principles, a pneumatic eye can be provided in which the oscillator is made to oscillate in the absence of an object and is rendered nonoscillatory in the presence of an object. The pressure of the power stream in

oscillator 10" is set within one of the aforesaid critical ranges, and the pressure of the control jet issuing from nozzle 41 is made just great enough to produce a slight disturbance in control tube 35" sufficient to upset the delicate pressure balance in region 23 and initiate oscillation in oscillator 10". When a detected object is disposed to block the jet from nozzle 41, the oscillations cease. Similarly, if it is desired to provide pneumatic eye operation in which oscillation signifies a detected object, the power stream pressure can be set just outside of one of the critical pressure ranges so that receipt of the low pressure detection stream at control tube 35" inhibits oscillation. When a detected object blocks the detection stream, the oscillations resume to signify detection.

In either of the above operational modes, detection is extremely sensitive. In fact, organ pipe oscillator 10" has been found to respond (i.e., change from oscillatory to nonoscillatory modes and vice versa) to acoustic disturbances received by control tube 35" independently of the detection stream issued by nozzle 41. Thus a prowler detector is provided.

While the pneumatic eye of FIG. 3 as thus far described provides a temporary indication (oscillation or nonoscillation) in response to a disturbance in control tube 35", the pneumatic eye may also be operated so as to have a memory feature; that is, the condition (oscillation or nonoscillation) to which oscillator 10" is switched in response to a disturbance may be retained after the disturbance ceases. The memory feature is achieved by setting the power stream pressure sufficiently close to a boundary pressure in one of the above-described critical pressure ranges. Thus, by setting the power stream pressure within and at the very end of a critical range, a disturbance will produce oscillation that is maintained even after the disturbance is removed. Similarly, setting the power stream pressure just outside one of these critical pressure ranges results in oscillations being inhibited in response to a disturbance and remaining inhibited after the disturbance ceases. The reason for the memory capability of oscillator 10" when the power stream pressure is set as stipulated is a hysteresis effect in the frequency versus power stream pressure characteristic of the unit.

In still another pneumatic eye embodiment of the present invention utilization is made of a second control nozzle 43 which issues a second control stream in interacting relationship with the control stream issued from control nozzle 41. The nozzles are arranged so that the object to be detected passes through the path of the stream issuing from control nozzle 43, and the detection of such an object may either produce or inhibit oscillation in oscillator 10". Thus oscillator 10" may be biased as described above to oscillate when no stream is received in tube 35", the stream issued from control nozzle 43 normally deflecting the stream issued from control nozzle 41 away from control tube 35". Oscillator 10" continues to oscillate until such time as an object is detected in the path of the stream issuing from control nozzle 43. This prevents deflection of the stream issuing from control nozzle 41, which stream thereby enters control tube 35" at a sufficient pressure level to destroy the standing wave patterns therein and inhibit oscillation.

Conversely the pressure level of the power stream can be set in accordance with the critical pressure ranges discussed to provide an oscillatory signal from oscillator 10" only when an object is detected in front of nozzle 43, the oscillations being otherwise inhibited. Likewise, the memory feature discussed above may be employed by utilizing biasing techniques discussed above.

In a particular embodiment of the pneumatic eye built and tested, excellent results were achieved with a distance between control tube 35" and control nozzle 41 of 1 foot and a distance from control nozzle 43 to the jet issued from control nozzle 41 of 3 feet. Of course, larger or smaller distances are possible, these being employed as a function of the pressure levels utilized.

From the above description, it should be apparent that the stream issued from nozzle 41 need not be directed axially into

tube 35". Specifically, the stream may be directed in any manner which causes a disturbance sufficient to alter the standing wave patterns in the tube.

In addition to the above-described embodiment, numerous other applications of the condition responsive organ pipe oscillator described herein may come to mind from the above disclosure. Specifically, logic elements such as NOR, AND, OR and NAND gates may be constructed whereby an oscillatory output signal is produced or not as a function of the various input signals which direct or deflect the control stream from nozzle 41 relative to control tube 35" of FIG. 3 as a function of the logic desired. The advantage of such an application is the high gain output signal produced in the form of the oscillating power stream signal received by passages 29 and 31.

Of course, the precise configuration of oscillator 10 of FIG. 1 should not be construed as limiting. For example, the oscillator may have opposed control tubes such as the oscillator described in U. S. Pat. No. 3,340,884 to R. W. Warren and R. E. Bowles rather than a single control tube as illustrated herein. Further, the region 23 may be constructed such that the open area to the left of the power stream, as viewed in FIG. 1, is closed off by a sidewall which would render the power stream bistable. More specifically, the power stream would lock-on to one or both sidewalls, to be displaced only by a force sufficient to overcome lock-on provided against the power stream.

While I have described and illustrated one specific embodiment of my invention, it will be clear that variation of the details of construction which are specifically illustrated and described may be resorted to without departing from the spirit and scope of the invention as defined in the appended claims.

I claim:

1. A condition responsive oscillator comprising:
a pure fluid amplifier having a power nozzle responsive to pressurized fluid applied thereto for issuing a power stream, at least one output passage for selectively receiving said power stream, and means for developing cyclically varying pressure differentials across said power stream, said means comprising at least one control tube having a predetermined length and having one end located adjacent the power stream such that power stream flow thereby produces a disturbance in the control tube resulting in the generation of standing waves therein, the length of said standing waves being determined by the length of said control tube, whereby the power stream is cyclically deflected relative to said output passage at a frequency determined by the length of said control tube; and
control means responsive to said condition for varying the effective length of said standing waves as a function of said condition.

2. The combination according to claim 1 wherein said control means comprises a piston member disposed within said control tube and translatable axially therealong as a function of said condition to vary the effective length of said control tube.

3. The combination according to claim 2 wherein said means for translating comprises a shaft secured to said piston member and means for translating said shaft axially along said control tube as a function of said condition.

4. The combination according to claim 2 wherein said control tube is closed at its end remote from the power stream, 65 said piston member being translatable in said control tube as a function of translation of said control tube along its axis.

5. The combination according to claim 4 wherein sufficient clearance is provided between said piston member and the interior of said control tube as to render friction therebetween 70 negligible.

6. The combination according to claim 4 further comprising means for providing a restoring force to said piston member in response to translation thereof in said control tube, said restoring force being proportional to the displacement of said

piston from a predetermined position relative to said control tube.

7. The combination according to claim 1 wherein said control means includes a control nozzle for producing a flowing fluid stream directed against the end of said control tube remote from said power stream, said power stream being rendered oscillatory and nonoscillatory in accordance with the presence and absence of said flowing fluid stream in said control tube.

10 8. The combination according to claim 7 wherein the pressure of said pressurized fluid applied to said power nozzle is such that said power stream is rendered oscillatory by said standing waves in the absence of said flowing fluid stream in said control tube, and wherein the pressure of said flowing fluid stream is sufficient to render said power stream nonoscillatory when received in said control tube.

9. The combination according to claim 8 wherein is further provided a further control nozzle for issuing a further fluid stream which deflects said flowing fluid stream, whereby interruption of said further fluid stream permits reception of said flowing fluid stream in said control tube to inhibit oscillation of said power stream.

10 10. The combination according to claim 7 wherein the pressure of said pressurized fluid applied to said power nozzle is such that said power stream is rendered nonoscillatory in the absence of any disturbance of said control tube, and wherein the pressure of said flowing fluid stream is sufficient to initiate oscillation of said power stream when received by said control tube.

11 11. The combination according to claim 10 wherein the pressure of said pressurized fluid applied to said power nozzle is such that said power stream is rendered nonoscillatory in the absence of any disturbance of said control tube, and wherein the pressure of said flowing fluid stream is sufficient to initiate oscillation of said power stream when received by said control tube.

12. The condition responsive oscillator according to claim 1 further comprising utilization means responsive to the frequency of deflection of said power stream.

13. The condition responsive oscillator according to claim 12 wherein said utilization means is a pressure sensitive device connected to said output passage.

14. The condition responsive oscillator according to claim 1 wherein said pure fluid amplifier includes an interaction region with which said power nozzle, output passage and control tube communicate and into which said power stream is issued generally toward said output passage, said one end of said control tube being disposed at one side of said interaction region, the opposite side of said interaction region being open to ambient pressure.

15. The condition responsive oscillator according to claim 14 wherein said opposite side of said interaction region is so configured to conduct acoustic vibrations transmitted by the cyclically deflected power stream, and further comprising transducer means for converting acoustic vibrations so conducted into signals.

16. A condition responsive oscillator comprising:
a fluidic element having a power nozzle responsive to pressurized fluid applied thereto for issuing a power stream, at least one output passage for selectively receiving said power stream, and means for developing cyclically varying pressure differentials across said power stream, said means comprising at least one control tube containing a column of ambient fluid and having an open end located adjacent the power stream such that the power stream flow thereby disturbs the ambient fluid in said control tube resulting in the generation of standing waves therein, the length of said standing waves being determined by the length of said column of ambient fluid, said standing waves cyclically deflecting said power stream at a frequency determined by the length of said column of ambient fluid in said control tube; and

control means responsive to said condition for varying the length of said column of ambient fluid in said control tube as a function of said condition.

17. The combination according to claim 16 wherein said

control means comprises a piston member disposed within said control tube and translatable axially therewith as a function of said condition.
